UNITED STATES PATENT OFFICE

112,942

DESIGN FOR A VENDING MACHINE

Lue O. Garner and Fred Montesi, Memphis, Tenn.

Application August 3, 1938, Serial No. 79,065

Term of patent 14 years

To all whom it may concern:

Be it known that we, Lue O. Garner and Fred Montesi, both citizens of the United States, residing at Memphis, in the county of Shelby and State of Tennessee, have invented a new, original, and ornamental Design for Vending Machines, of which the following is a specification, reference being had to the accompanying drawing, forming part thereof.

Fig. 1 is a perspective view showing the front and one side of the casing of our vending ma-

chine, both sides of the casing having glass doors, and the view including such interior portions of the machine as are visible through the glass door of the side shown. The opposite side of the machine is substantially identical.

Fig. 2 is a rear elevation of the casing.

We claim:

The ornamental design for a vending machine, substantially as shown and described.

LUE O. GARNER.
FRED MONTESI.
